(57) CLAIM

The ornamental design for a decorative tea, as shown and described.

DESCRIPTION

FIG. 1 is a perspective view of a decorative tea showing our new design;

FIG. 2 is a top view thereof;

FIG. 3 is a bottom perspective view thereof; and,

FIG. 4 is a side perspective view thereof.

The broken lines are included for the purpose of illustrating environmental structure and form no part of the claimed design.

1 Claim, 4 Drawing Sheets
